PNEUMATIC SEPARATOR FOR PULVERIZING MILLS

Filed Dec. 19, 1927

UNITED STATES PATENT OFFICE

WILSON L. McLAUGHLIN AND HERROLD L. McLAUGHLIN, OF DES MOINES, IOWA

PNEUMATIC SEPARATOR FOR PULVERIZING MILLS

Application filed December 19, 1927. Serial No. 241,200.

The principal object of this invention is to provide an efficient device to be used in connection with a pulverizing mill for pneumatically separating the coarser particles from the fine material and returning the former to the pulverizing chamber of the mill.

More specifically, the object of this invention is to provide a pneumatic separator for pulverizing mills comprising, a receiving chamber communicating with the pulverizing chamber of the mill, a trough in the receiving chamber so placed and positioned that the material impregnated air must pass around and over the same, and return pipes communicating with the bottom of the trough and the inside of the mill pulverizing chamber.

A further object of this invention is to provide an apparatus for separating coarse particles from fine material, which is of such form and construction that the granular material pneumatically induced from a pulverizing mill is caused to be divided and again to meet directly over a horizontal trough, thereby permitting the coarser particles to settle in the trough by the action of the two streams coming together above a calm that exists slightly below the contact points of the two streams of material laden air.

A still further object is to provide a separator for separating coarse particles from fine material laden air or gas that is capable of obtaining the desired coarseness of material from the air or gas.

A still further object of this invention is to provide a separator that is economical in manufacture and durable in use.

These and other objects will be apparent to those skilled in the art.

Our invention consists in the construction, arrangement and combination of the various parts of the device, whereby the objects contemplated are attained as hereinafter more fully set forth, pointed out in our claims and illustrated in the accompanying drawing, in which:

Fig. 1 is a side sectional view of our complete device mounted on a pulverizing mill and ready for use.

Fig. 2 is a top plan sectional view taken on line 2-2 of Fig. 1 and shows the trough por-

tion of the device correctly mounted in the receiving chamber.

Fig. 3 is a perspective view of the trough portion of the separator and more fully illustrates its construction.

Machines for the pulverizing of material such as coal and the like, use a current of air to remove from the machine the particles that have been finely ground in the pulverizing chamber. This current of air leads to a separator either of the bag or centrifugal type for removing the comminuted material from the air. However, if one inspects the material obtained by the separators, it will be found that much coarse matter that should never have left the pulverizing mill exists in the finely ground material. This is objectionable and it is the purpose of our separator to prevent this coarse material from entering the fabric or centrifugal separator.

We have designated the ordinary pulverizing chamber of a mill by the numeral 10, which consists of a plurality of side plates secured together by suitable means. In the upper portion of this chamber is the opening 11 for the inserting of material in the pulverizing chamber. Rotatably mounted in two sides of the pulverizing chamber 10 is a shaft 12 upon which is permanently secured the cylinder 13 having the pulverizing hammers 14. The shaft 12 is designed to be rotated in the ordinary manner by a prime mover (not shown). The numeral 15 designates a receiving chamber secured in the upper forward portion of the pulverizing chamber and communicating with the same. At the top and near the center of this receiving chamber is an outlet pipe 16 communicating with an induction fan 17, shown in conventional form in Fig. 1 and designed to be rotated by the electric motor 18. The numeral 19 designates an outlet pipe from the induction fan to an ordinary fabric or centrifugal separator (not shown). Mounted in the receiving chamber 15, extending the full length of the same and directly under the outlet pipe 16 is the trough 20. The numeral 21 designates return lead pipes, each having one of their ends communicating with the bottom of the trough 20 and their other ends terminat-

ing alongside the inner walls of the pulverizing chamber. The numeral 22 designates an inlet pipe communicating with the inside of the pulverizing chamber as shown in Fig. 5 1. The weight of the fan 17 and electric motor 18 is supported on a landing, which we have designated by the numeral 23. Mounted in the pipe 16 is a gate valve 24 for limiting the amount of air drawn through 10 the pipe 16 by the fan 17.

The practical operation of the device is as follows: The material 25 is placed in the pulverizing chamber through the opening 11 where the rotating hammers 14 eventually 15 reduce it to a pulverized state. If the electric motor 18 is rotating the fan 17, a current of air will be drawn through the pipe 22, through the pulverizing chamber, through the receiving chamber 18, and forced 20 into the fabric or centrifugal separator, not shown. This current of air passing through the pulverizing chamber will naturally gather with it, the material in the pulverizing chamber that has been reduced to impalpability. This air also catches coarser particles 25 and carries the same from the pulverizing chamber before they are reduced to comminuted state. However, due to the construction and placement of the trough 20, the material impregnated air is caused to divide and pass on each side of the trough, as shown in Fig. 1. As the outlet pipe 16 is directly above the trough 20, the two streams of air must come in direct contact with each other 30 over the trough 20; the heavier particles striking each other and falling into the trough 20 where they pass through the pipes 21, back into the pulverizing chamber. By the opening or partially closing of the gate 35 valve 24, the material laden air passing through the pipe 16 will be proportionately regulated. If the gate is partially closed, the force of air passing around and over the trough 20 will be greatly reduced and 40 the more finer of the coarser particles carried by the air will drop into the trough. In other words, any degree of fineness of 45 the particles desired to be returned to the pulverizing chamber may be realized by the adjusting of the valve 24. Also, it will be 50 found that still air exists in and slightly above the trough and the heavier particles, which are naturally at the bottom of each 55 current of air, readily experiences this still air which cannot support it and they descend into the trough 20.

From the foregoing, it will readily be understood by those skilled in the art that we have provided an apparatus that will eliminate 60 the undesirable coarse material from a pulverizing device from reaching the fabric or centrifugal separator.

Some changes may be made in the construction and arrangement of our improved 65 pneumatic separator without departing from

the real spirit and purpose of our invention and it is our intention to cover by our claims any modified forms of structure or use of mechanical equivalents which may be reasonably included within their scope.

70

We claim:

1. In a device of the class described, a receiving chamber having an inlet and an outlet opening, a means for passing a current of air through said chamber, a trough so positioned in said receiving chamber that the current of air passing through the receiving chamber must divide into two streams and again joint into one stream directly above the said trough, and pipes having one end communicating with the inside of said trough, extending downwardly in said receiving chamber and terminating at a point at the side of the main current of air passing through said chamber.

75

2. In a device of the class described, a receiving chamber having an inlet opening in its bottom, an outlet pipe communicating with the top of said receiving chamber, a means for drawing a current of air through said receiving chamber and outlet pipe, a valve in said outlet pipe for restricting its opening, a trough in said receiving chamber and directly below said outlet pipe, and a pipe communicating with the inside and bottom of said trough, extending downwardly in said receiving chamber and terminating of the point to the side of the main column of air passing through said chamber.

80

3. In a device of the class described, a housing having an inlet opening in its bottom portion, an outlet pipe communicating with the inside of said housing at a point near its top, a means for passing a current of material impregnated air through said housing, a trough pointed at its bottom in the path of said upwardly passing current of material impregnated air capable of dividing said current into two distinct streams, and a pipe leading downwardly and outwardly from said trough for obtaining the material collected by said trough and depositing the same to the side of the main current of material impregnated air passing through said housing.

85

4. In a device of the class described, a housing having an inlet opening in its bottom and an outlet opening in its top, a means for passing the current of material impregnated air up through said housing, and an elongated trough extending from two sides of said housing and in the path of the current of said material impregnated air for dividing the same into two distinct streams and allowing them to meet and strike each other directly over its open top, and a pipe leading from said trough for obtaining the material collected by said trough and depositing the same at one side of the current of

material impregnated air passing upwardly through said housing.

5. In a device of the class described, a separator housing having an inlet opening, an outlet pipe communicating with the inside of said separator housing at a point in its top portion, a means for passing the current of material impregnated air through said separator housing, a material receiving trough 10 pointed at its bottom for dividing said current of material impregnated air into two distinct streams and allowing them to meet again directly above its open top; said trough having its upper marginal edges considerably 15 lower than the lower marginal edge of said outlet pipe, and a pipe having one end communicating with the inside of said trough, extending downwardly and to one side of said separator housing and terminating at a 20 point outside the main current of the material impregnated air.
